UNITED STATES PATENT OFFICE.

FRANKLIN W. OEHRL, OF PHILADELPHIA, PENNSYLVANIA.

DESIGN FOR WOVEN EDGING.

40,364.

Specification for Design.

Patented Nov. 16, 1909.

Application filed September 18, 1909. Serial No. 518,459. Term of patent 7 years.

To all whom it may concern:

Be it known that I, FRANKLIN W. OEHRL, a citizen of the United States, residing in Philadelphia, Pennsylvania, have invented a new, original, and ornamental Design for Woven Edging, of which the following is a specification, reference being had to the accompanying drawings, forming part thereof.

The figure is a face view of a piece of woven edging showing my new design.

I claim:

The ornamental design for a woven edging as shown.

FRANKLIN W. OEHRL.
